UNITED STATES PATENT OFFICE

2,539,798

FUEL INJECTION SYSTEM

Hans G. Spier, Hamilton, Ohio, assignor to American Bosch Corporation, Springfield, Mass., a corporation of New York

Application October 10, 1945, Serial No. 621,463

3 Claims. (Cl. 123—139)

1

This invention relates to fuel injection systems for internal combustion engines and has particular reference to such a system which is completely pressure operated and has no mechanical connection with the engine pistons.

An object of the invention is to provide a new and improved fuel injection system for internal combustion engines which is completely pressure operated and has no mechanical connection with the engine pistons.

Another object of the invention is to provide a new and improved fuel injection system for use with free piston engines.

Another object of the invention is to provide a new and improved fuel pump for fuel injection systems for free piston engines which is operated by the direct bounce pressure for pumping fuel.

Another object of the invention is to provide a new and improved injection timer for a fuel injection system.

Another object of the invention is to provide a new and improved injection timing system for a fuel injection system, which system is operated by delayed pressure rise.

Another object of the invention is to provide a new and improved injection timing system for a fuel injection system which is operated by pressure.

Another object of the invention is to provide a new and improved injection timing system for a fuel injection system, which timing system is operated by cylinder pressure.

Another object of the invention is to provide a new and improved injection timing system for a fuel injection system, which timing system is operated by pressure from the reverse bounce cylinder.

Another object of the invention is to provide a new and improved adjusting means for a pressure operated injection timing system of a fuel injection system.

Other objects and advantages of the invention will be apparent from the following description taken in connection with the accompanying drawings. It will be understood that many changes may be made in the details of construction and arrangement of parts without departing from the spirit of the invention as expressed in the accompanying claims. I, therefore, do not wish to be limited to the exact details of construction and arrangement of parts shown and described as the preferred form has been given by way of illustration only.

Referring to the drawings:

2

Fig. 1 is a sectional view of a fuel injection system embodying the invention;

Fig. 2 is a sectional view of a fuel pump for use therewith;

5 Fig. 3 is a fragmentary view of Fig. 1 on an enlarged scale;

Fig. 4 is a diagram illustrating the operation of the injection timing system;

10 Fig. 5 is a diagrammatic view of a fuel injection system embodying the invention and includes a view taken on line 5—5 of Fig. 6 looking in the direction of the arrows;

Fig. 6 is a fragmentary side view of the combustion chamber shown in Fig. 5; and

15 Fig. 7 is a sectional view taken on line 7—7 of Fig. 6 looking in the direction of the arrows.

Referring more particularly to the drawings wherein similar reference characters designate corresponding parts throughout the several views,

20 the device shown embodying the invention comprises three elements, namely the accumulator nozzle and trip mechanism 1, the injection timer 2 and the fuel pump 3.

The accumulator nozzle and trip member 1 is positioned in alignment with an opening in the wall 4 of the engine cylinder and is secured to said wall and is adapted to inject fuel into the combustion chamber of the engine. The said member 1 is connected to the fuel pump 3 by a pipeline 1a which pipeline is connected to the coupling 5 on the fuel pump 3 at one end and to the coupling 6 on the member 1 at its other end to provide a fuel pressure supply to the member 1. The direct bounce chamber is connected to fuel pump 3 by pipe line 3a.

25 The member 1 is also provided with the coupling 7 to which a drain pipe 7a is adapted to be connected for draining off any leakage or excess fuel in the member 1.

30 40 The member 1 is connected to the injection timer 2 by the pipeline 8.

The said member 1 includes the tip 9 which extends through and is secured to the wall of the cylinder 4, and also includes the accumulator body portion 10 and the piston valve portion 11 with said members having an aligned opening closed by the closing plug 12.

35 45 50 The member 9, accumulator body portion 10 and piston valve portion 11 are positioned in alignment and are retained in said alignment by the threaded nut 14, the threaded portion of which engages a threaded portion of the clamping sleeve 13 adjacent the upper end of said clamping sleeve 13, said nut 14 engages the annular washer 15 between the lower end of the

nut 14 and the outer surface of the flange on the piston valve portion 11 and when the nut 14 is tightened, the parts are retained in aligned operative relation. The dowel or locking pin 15a is provided in order to insure proper alignment between the parts.

Surrounding the clamping sleeve 13 is provided the jacket 16 which has its upper end 17 secured to the clamping sleeve 13 by brazing or other suitable means and surrounding the said jacket 16 is positioned the bushing 18 having the flange 19 adapted to engage the clamping ring 20. Between the flange 21 and the flange 22 on the clamping sleeve 13 are positioned the hold-down springs 22a.

Between the clamping sleeve 13 and the jacket 16 is a cooling space or chamber 23 adapted to receive water or other cooling agent through a line not shown which may be connected to the coupling 24 and said cooling agent may be exhausted through a pipeline connected to the coupling 25 to allow the passage of a stream of such cooling agent to pass into said chamber 23 through the coupling 24 and to be exhausted therefrom through the coupling 25 whereby the nozzle may be cooled by the continuously passing therearound of a continuous stream of said cooling agent.

Surrounding the nozzle tip 9 is positioned the cooling sleeve 26 which allows said cooling agent to surround said nozzle tip 9 between said sleeve 26 and the nozzle tip.

Between the cooling sleeve 26 and the bushing 18 and also between the jacket 16 and the bushing 18 is the space 27 to allow the draining of any superfluous fuel which may be exhausted through the opening 28 at the upper end of the bushing 18.

Within the nozzle tip 9 is the needle valve 29 which has an extension 30 extending into the accumulator chamber 31 with said extension 30 having a flange 32 on which is positioned the washer 33 supporting an end of the coil spring 34, the opposite end of which rests against the washer 35.

Within the piston valve portion 11 is positioned the piston or flash valve 36 having the enlarged end portion 37 against which rests the washer 38 against which is positioned the coil spring 39 which surrounds said piston or flash valve 36. The piston 36a, which is actuated by pressure through the line 8, in turn actuates the flash valve 36.

The passageway 40 is provided connecting and communicating between the cylinder for the piston or flash valve 36 and the accumulator chamber 31 through the check valve 41.

The piston or flash valve 36 has the reduced portion 42 communicating with the fuel pressure line supply 6 and the passageway 40 when the piston or flash valve 36 is in the position shown to allow fuel from the pressure supply 6 to enter said passageway 40 and through the check valve 41 to the accumulator chamber 31 from which the fuel is consequently injected into the combustion chamber of the engine through the nozzle tip 9.

The upper end of the piston or flash valve 36 has a reduced portion 42 forming a fuel receiving chamber adapted to be aligned with the fuel inlet coupling 6 when the flash valve 36 is in the position shown and adapted to close said fuel supply line 6 when moved downward by action of the injection timer. The cylinder for the piston 36 is connected to the drain 7 for superfluous

fuel by the passageway 43. When the pressure through the pipeline 8 is strong enough to overcome the action of the coil spring 39, the piston or flash valve 36 is moved downward sufficiently to close the fuel inlet passage 6, as stated above, and connects fuel line 40 to drain line 7 through the relief section of valve 36 and releases the pressure of the fuel on top of the needle 30 allowing the needle valve to be opened by the force of fuel trapped under pressure in the accumulator chamber 31 which acts on the under side of piston 36a and lifts the needle valve from its seat and injects the fuel into the engine cylinder. The operation of the accumulator nozzle is generally similar to the operation of prior accumulator nozzle systems except for the injection timer and, therefore, the operation of the accumulator system need not be given in further detail here.

The injection timer comprises a tubular body portion 44 extending through the wall 4 of the cylinder and secured thereto and having a needle valve 45 communicating therewith adapted to receive pressure from the cylinder for operation of the injection timer.

Surrounding the said body portion 44 is the jacket 46, and there is provided a space 47 between the body portion 44 and said jacket 46 whereby a stream of a cooling medium may be introduced through the coupling 48 and exhausted through the coupling 49 for cooling the heated cylinder gas entering said body from the cylinder.

Within the body portion 44 is the adjustable restriction member 50 which has a threaded portion 51 adapted to be adjusted by turning the extension 52 to adjust the restriction member 50 within the body portion and thereby adjust the delayed pressure rise of the injection timing arrangement as hereinafter described.

The fuel pump 3, as shown in Fig. 2, comprises the body portion 54 having the opening 53 in its lower end adapted to be connected by a line 53a to the combustion chamber or to the direct bounce compression chamber of the engine outside of the end of a piston in order that the pump may be operated by the cylinder pressure.

The pump is adapted to receive fuel from a fuel supply through the coupling 54a to which 50 may be connected a pressure line from the fuel supply tank and the fuel passes throughout the inlet check valve 55 to the metering and pumping cylinder 56 which is closed by the closing plug 57 and then to be pumped by the pumping plunger 58 through the delivery valve 59 through the coupling 5 to a pipeline 5a connected with the coupling 6 of the accumulator nozzle and trip mechanism as previously described.

Within the pump body 54 are the piston rings 60 adapted to be actuated by the cylinder pressure to cause movement of the pumping plunger 58 against the action of the coil spring 61 to pump the fuel after which the pumping plunger 58 is returned to pumping position by the action of said coil spring 61 after the cylinder pressure is reduced. The volume thus pumped may be controlled by a means of restricting the supply flow to the check valve 55 such as the valve 64, or other suitable means.

The diagram in Fig. 4 shows the relationship between cylinder pressure and the delayed pressure rise caused by the restriction 50 of the triggering means for actuating the fuel injection apparatus. It will be noted that the restriction acts as a time delay to delay the pressure rise and

that pressure in the pressure chamber 62 of the injection timer 2 will be rising rapidly when pressure in the cylinder is high and that the amount of delay will be controlled by the size of the leakage allowed by the restriction 50 and the volume of the pressure chamber 62.

In the diagram shown in Fig. 4, line A represents the rise and fall of pressure in the cylinder and dotted line B represents the rise and fall of pressure in the pressure chamber of the injection timer, D is the point where line A crosses the highest point of line B and C and E are the points where line A crosses line B at the lowest point of line B. A study of this diagram will show how the pressure rise in the pressure chamber is delayed by the triggering mechanism. This pressure rise in the pressure chamber may be adjusted through adjustment of the restriction 50 by turning the adjusting screw 52 as previously described. By means of this adjustment the rise of pressure in the pressure chamber may be speeded up or slowed down to alter the relation between the pressure rise in the cylinder and the pressure rise in the pressure chamber and thereby increase or decrease the time lag between the cylinder pressure rise and the operation of the injection apparatus.

A further means of controlling the timing consists of varying the pressure of spring 39 thereby changing the point on the pressure rise curve 30 (Fig. 4) at which the pressure is sufficient to move the flash valve 36 into the lower position.

It is pointed out that the injection timer can also be connected to any other cylinder of the engine which has the desired pressure rise characteristic to effect the injection timing functions as, for instance, a reverse bounce cylinder on a free piston engine which cylinder is a cylinder acting to force the pistons in the same direction as does the power cylinder, that is, it is the cylinder opposing the action of the direct bounce cylinder which, in turn, opposes the action of the power cylinder.

The direct bounce cylinder or chamber of a free piston engine is that portion of the cylinders which returns the pistons to the combustion chamber and is particularly satisfactory because it has a considerable volume and pressure of air available and also the pressure rises at a convenient point in the stroke.

It is pointed out that the device as shown and described operates entirely by pressure, that is, the injection pump operates by pressure from the fuel line whereas the injection timer operates by delayed pressure rise from the cylinder pressure and the fuel pump operates also by cylinder

pressure and thereby the whole apparatus is pressure operated and requires no mechanical connection with the engine pistons thereby lending itself particularly for use with free piston engines although its use is not restricted to such engines.

It is pointed out that the transmission of the gas pressure wave from the timer body 2 to the flash valve can also be made hydraulically or mechanically if desired.

From the foregoing it will be seen that I have provided simple, efficient and economical means for obtaining all of the objects and advantages of the invention.

Having described my invention, I claim:

1. In a device of the character described, a nozzle, a fuel pump for supplying fuel to said nozzle, a pressure operated injection timing means for timing injections by said nozzle, and a restriction between the source of pressure and said injection timing means for causing a substantial delay in the pressure rise at said timing means.

2. In a device of the character described, a nozzle, a pressure operated fuel pump for supplying fuel to said nozzle, a pressure operated timing means including a pressure chamber, and a restriction between the source of pressure and said chamber whereby a substantial delay will be caused in the pressure rise at said timing means.

3. In a device of the character described, a nozzle, a pressure operated fuel pump for supplying fuel to said nozzle, a pressure operated timing means, a passageway connecting said timing means with the direct bounce chamber of an internal combustion device and a restriction in said passageway for causing a substantial delay in the pressure rise in said timing means.

HANS G. SPIER.
